UNITED STATES PATENT OFFICE.

FRANCIS M. CASE, OF CLEVELAND HEIGHTS, OHIO, ASSIGNOR TO BARTON R. DEMING,
OF CLEVELAND, OHIO.

COMBINED TABLE AND IRONING-MACHINE SUPPORT.

Application filed October 26, 1925. Serial No. 64,754.

This invention relates to a combined table and ironing-machine support, and has for its object to conserve space in a kitchen by providing a combined table and ironing machine in which the table top is so mounted on the supporting frame that its position thereon may be reversed, and the ironing mechanism is so mounted on the reversible top that in one position of the top it is with-
5 in the frame beneath the top and in the re-
versed position of the top it is in operative
10 position above the top.

A further object of the invention is to provide a combination table and ironing ma-
chine in which the frame is so constructed
15 and the top is so mounted on the frame that when the top is in position for ironing the space beneath the forward portion of the top is entirely clear and ample knee room
20 is provided.

A further object of the present invention is to provide a reversible top ironing ma-
chine in which the weight of the ironing mechanism acts to hold the top in engage-
25 ment with fixed stops in either of its re-
versed positions so that no locking means is required for retaining the top in either of its positions, and the top can be moved from either of its positions to the reverse position
30 by lifting upon one edge or the other there-
of.

A further object of the invention is to so locate the fixed stops that they are entirely clear of the table in all positions thereof
35 except that in which the table is held by the stops so that it is unnecessary to cut away any portion of the top to clear the stop lugs.

A further object is to so mount the ironing mechanism upon the top that when the ironing mechanism is in operative position the top at the side of the ironing mechanism from which the goods are fed to the ironing roll projects beyond the side of the frame
45 and forms a platform upon which the goods may rest while being fed to the ironing roll.

With the above and other objects in view the invention may be said to comprise the ironing machine as illustrated in the accom-
50 panying drawings hereinafter described and particularly set forth in the appended claims, together with such variations and modifications thereof as will be apparent to one skilled in the art to which the invention
55 appertains.

Reference should be had to the accom-
panying drawings forming a part of this
specification in which Fig. 1 is a perspective
view showing the ironing mechanism in op-
erative position; Fig. 2 is an end elevation
60 of the machine showing, in full lines, the
top so positioned that the ironing mecha-
nism is beneath it and within the frame, and
showing in dotted lines, the ironing mecha-
nism in operative position; Fig. 3 is a dia-
65 grammatic plan view of the supporting
frame showing the bracing of the legs; Fig.
4 is a fragmentary end view showing the
pivotal connection between the top and
frame at the end thereof opposite that shown
70 in Fig. 2.

Referring to the accompanying drawings
the supporting frame consists of front and
rear supporting legs 1 and 2 connected by
horizontal end bars 3 which are connected
75 to the tops of the front legs, and to the
rear legs which are higher than the front
legs, below the tops thereof, the legs being
also braced and connected by converging
connecting bars 4 connected to each pair of
80 end legs below the bars 3, the apices of the
bars 4 being connected by a horizontal lon-
gitudinal bar 5. The upper end portion 6
of the rear legs 2 extend above the end bars
3 and the extensions 6 are connected by a
85 panel 7. The end bars 3 are connected to
the outer sides of the legs 1 and 2 and the
center portion of the bars are offset outward-
ly to a slight extent between the front and
rear legs to provide clearance for the swing-
90 top as will be hereinafter more fully ex-
plained.

Intermediate the ends thereof the end bars
3 have integral posts 8 extending upward-
ly therefrom, these posts being located at a
95 point nearer the front of the frame than the
rear thereof, each post 8 being provided with
an open trunnion receiving socket 9 at the
upper end thereof. The table top 10 has
secured upon one face thereof at one end a
100 supporting bracket 11, which has an out-
wardly projecting boss 12 carrying a trun-
nion 3 which is adapted to fit within the
socket 9 at the upper end of the post 8 on
the adjacent bar 3. At the opposite end of
105 the top there is a mechanism housing 14
which carries a second trunnion 13 in axial
alignment with the trunnion 13 and adapted
to engage the socket 9 of the post 8 on the
cross bar 3 at that end of the frame. The
110

trunnions 13 and 13^a are positioned at points nearer one longitudinal edge of the top than the other so that when the top 10 is in the position shown in Fig. 2 of the drawing, one edge thereof is even with the rear side of the frame and the opposite edge thereof is even with the front side of the frame, and when the table is in the reversed position shown in Fig. 1, a portion thereof projects 10 out past the front of the frame.

Posts 15 are secured by hinges 16 to the same face of the top 10 as the supporting bracket 11 and housing 14, the posts 15 being mounted adjacent opposite ends of the 15 table at the longitudinal edge thereof which is closest to the trunnion posts 11 and connected by a panel 17. When the table is in the position shown in Fig. 2 of the drawing, the posts 15 rest upon the tops of the legs 20 1 while the opposite edge portion of the top 10 is resting upon the tops of the extension 6 of the rear legs 2, the panel 17 in this position corresponding to the panel 7 at the rear of the frame. The end bars 3 are off- 25 set outwardly a sufficient distance to permit movement of the top 10 between them, and the upper ends of the legs 1 are cut away sufficiently at their inner corners to permit the edge of the top 10 to which the pivoted 30 posts 15 are attached to clear the legs as the table is swung about the trunnions 13 and 13^a to shift it from the position shown in Fig. 2 to the position shown in Fig. 1. The posts 15 can be swung inwardly from the 35 position shown in Fig. 2 until they are clear of the upper ends of the legs 1, thus releasing the top so that it can be swung to reversed position.

It will be noted that the pivotal movement 40 of the top in one direction is limited by the extensions 6 of the rear legs. Means is also provided for limiting the pivotal movement of the top in the opposite direction to substantially 180° so that the top may be moved 45 from the horizontal position shown in Fig. 2 to a reversed position by turning the top through 180° about its trunnions. The stops for limiting the swinging movement at the top and for retaining it in the reversed position, 50 are in the form of lugs 18 which are formed integrally with the end bars 3 and which project inwardly therefrom into the path of the movement of the table between the posts 8 and the rear of the frame. The 55 ironing mechanism is carried by the bracket 11 and housing 14 and is positioned at the side of the pivotal axis of the top opposite that with which the lugs 18 engage so that the weight thereof holds the top in engagement with the lugs.

The specific ironing mechanism employed 60 in immaterial to the present invention, but preferably comprises an ironing shoe 19 and a roll 20 mounted for movement toward and from the shoe. A feed board 21 may be pro-

vided in connection with the roll 20, and this board may be supported by arms 22 which may be pivotally and adjustably mounted on the shaft 23 of the roll, the feed board being held in adjusted position by a pin 24 70 carried by the roll supporting arm 25 and adapted to engage in any one of the openings 26 in the inner portion of the adjacent arm 22.

When the table top is in the position 75 shown in Fig. 1 the ironing mechanism is entirely in front of the pivotal axis of the table and the weight of the ironing mechanism acts to firmly hold the table in engagement with the under side of the stop 80 lugs 18 so that the mechanism is securely supported in operative position. In this position of the top the ironing mechanism is directly over the front portion of the frame and the top 10 projects outwardly beyond 85 the front of the frame forming a platform upon which the goods to be ironed may be placed. It should also be noted that the construction of the frame is such that the space between the forward portion of the 90 top when in ironing position is entirely unobstructed so that the operator while ironing may sit in a chair with her knees under the table at any point along the length thereof.

The top can be reversed from the position shown in Fig. 1 to that shown in Fig. 2 by simply lifting up on the forwardly projecting portion of the table causing the rear portion of the top to swing downwardly 100 away from the stop lugs 18. During this movement the ironing mechanism will be moved up over the trunnions 13 until the center of gravity thereof is shifted to the rear of said trunnions, whereupon the weight 105 of the ironing mechanism will carry the top on over into the position shown in Fig. 2 of the drawing in which position the weight of the ironing mechanism is between the trunnions 13 and the rear of the frame and acts to hold the table down upon the upper ends of the extensions 6 of the rear legs 2. During this movement of the top the 110 posts 15 will be swung inwardly to clear the inner sides of the legs 1 and when the top reaches horizontal position will swing outwardly into engagement with the upper ends of the legs 1. The stop lugs 18 are so positioned that they engage with edge 115 portions of the top in one position only of the top and so that in the movement of the top to the reverse position no portions of the top move past the lugs. Likewise the extensions 6 of the rear legs are engaged by an edge portion of the top in only one 120 position of the top and are cleared by the opposite edge of the top in the reversing movements thereof. Since the fixed stops are entirely clear of the edges of the top in its 125 reversing movements the necessity for cut- 130

ting away portions of the edge or providing stop engaging projections is eliminated and the top may be made with straight unbroken edges as is highly desirable when the ironing mechanism is folded into the frame and the table is being used as a kitchen table.

When the table top is in the position shown in Fig. 2 of the drawing one edge portion overlies the extension 6 of the rear legs 2 and the opposite edge thereof overlies the pivoted posts 15 which rest upon the top of the legs 1 and form extensions thereof, the table legs in this portion of the top being entirely within the confines of the edges of the table as is desirable for a kitchen table.

Having described my invention what I claim is:

1. A combined table and ironing machine support comprising a frame having end members, a top extending substantially the full length of the frame and pivoted to the frame to swing about an axis fixed with respect to the top and frame and extending longitudinally of the top intermediate the side edges thereof, a fixed stop projecting inwardly from an end member in the path of movement of an edge portion of the top to retain the same in a horizontal position, said pivotal axis being so positioned with respect to said stop that said stop is entirely clear of the top during the movement thereof about its pivotal axis through an angle of 180° to reversed position, and a second fixed stop on the frame for supporting the top in reversed position.

2. A combined table and ironing machine support comprising a frame having end members, a top extending substantially the full length of the frame and pivoted to the end members to swing about an axis fixed with respect to the frame and top and extending longitudinally of the top intermediate the side edges thereof, a fixed stop carried by an end member in the path of movement of an edge portion of the top to retain the same in one horizontal position and a second fixed stop in the path of movement of an edge portion of the top to retain the same in reversed position, each of said stops being carried by the frame and so positioned with respect to the pivotal axis as to be clear of the top during its turning movement to a reversed position.

3. A combined table and ironing machine support comprising a frame having end members, a top extending substantially the full length of the frame and pivoted to the frame to swing about an axis fixed with respect to the frame and top and extending longitudinally of the top intermediate the side edges thereof, said axis being nearer one side edge of the top than the other, and fixed stops on said frame at different distances from the pivotal axis and at the same

side thereof, one stop being in the path of movement of an edge portion of the top at one side of the pivotal axis and another stop being in the path of movement of an edge portion of the top at the opposite side of the pivotal axis.

4. A combined table and ironing machine support comprising a frame having end members, a top extending substantially the full length of the frame and pivoted to the frame to swing about an axis fixed with respect to the frame and top and extending longitudinally of the top intermediate the side edges thereof, said axis being nearer one longitudinal edge of the top than to the other and spaced from the plane of the top, and fixed stops carried by the frame at different heights and at different distances laterally from said axis and at the same side of said axis, one of said stops being carried by an end member and in the path of movement of the side edge portion of the top nearest the pivotal axis, the other stop being in the path of movement of a portion of the top on the opposite side of the pivotal axis.

5. A combined table and ironing machine support comprising a frame having end members, a top extending substantially the full length of the frame and pivoted to said frame to swing about an axis fixed with respect to the top and frame and extending longitudinally of the top; said axis being nearer one longitudinal edge of the top than the other, and fixed stops on the frame in the path of movement of portions of the top and positioned to be engaged by portions of the top on opposite sides of the pivotal axis when it is in horizontal positions and to limit the movement of the top to substantially 180° , said top being centered with respect to the frame in one of its horizontal positions and offset with respect to the frame whereby it projects outwardly from the frame in the reverse position, said frame being formed to provide a clear space within the sides and ends thereof to accommodate the ironing machine beneath the top when the top is in the first-mentioned position and to permit movement thereof with the top to reversed position.

6. A combined table and ironing machine support comprising a frame having end members, a top having aligned trunnions at opposite ends engaging the end members of the frame, said trunnions being nearer one longitudinal edge of the top than the other, fixed bearings on the end members in which said trunnions fit, fixed stops on the frame in the path of movement of portions of the top and positioned to be engaged by the top when it is in horizontal positions and to limit the movement of the top to substantially 180° , the said top being centered with respect to the frame when in one position and offset with respect to the frame whereby

it projects beyond the front of the frame when in reversed position.

7. A combined table and ironing machine support comprising a supporting frame having end members, a reversible top extending substantially the full length of the frame and pivoted on the frame, said top being free to swing about an axis extending longitudinally of the frame and lying between the 10 longitudinal center plane of the frame and the front thereof, said frame having a ledge at the rear side thereof upon which the top is adapted to rest, said ledge being so positioned with respect to the pivot of the top 15 as to cooperate therewith to support the top in a horizontal position and a lug on an end member of the frame rearwardly of the pivot against the under side of which the top is adapted to bear when in reversed position. 20
8. A combined table and ironing machine support comprising a supporting frame and a reversible top pivoted on the frame and free to swing about an axis extending longitudinally of the frame and lying between the 25 longitudinal center plane of the frame and the front thereof, said frame having a ledge at the rear side thereof upon which the top is adapted to rest, said ledge being so positioned with respect to the pivot of the top as 30 to cooperate therewith to support the top in a horizontal position and a lug on the frame against the under side of which the top is adapted to bear when in reversed position, said top being so mounted on the pivot that when it is supported on said ledge and pivot 35 its opposite side edges are at the front and rear sides of the frame and when supported in engagement with the lug in reversed position it projects beyond the front of the frame, whereby the ironing machine may be so mounted upon the top that it is supported in upright position above the top and in front of the pivot of the top when the top is in engagement with said lug and beneath the 40 top within the frame when said cover is reversed and in engagement with said ledge.

9. A combined table and ironing machine support having a supporting frame with supporting ledges at the front and rear thereof, the rear ledge being higher than the front, a top pivoted to the frame to swing about a longitudinal axis nearer the front than the rear thereof and at a height substantially midway between said supporting ledges, said top being engageable in one position with the rear supporting ledge, a member pivotally connected to said top and adapted to engage the front supporting ledge when said top is resting on said rear ledge, and a lug on the frame forwardly of

the rear ledge between the same and the pivotal axis of the top and projecting into the path of movement of the top, said lug being engaged on the under side thereof by said top and serving to retain the top in reversed position. 70

10. A combined table and ironing machine support comprising a rectangular supporting frame having a pair of front supporting legs and a pair of rear supporting legs higher than the front supporting legs, horizontal side bars connecting the upper ends of the front legs to the rear legs and offset outwardly from said legs, a horizontal bar connecting the front legs, a panel 75 extending between the upper portions of the rear legs, posts extending upwardly from said side bars at points nearer the front of the frame than the rear thereof, a top having posts fixed to one face thereof at opposite ends, and having a panel secured to the same face thereof along one edge, axially aligned pivots connecting the posts on the side bar of the frame and the posts on the top, said posts and pivots being so disposed 80 that the top may be supported with the panel depending therefrom directly over the front posts and with the opposite edge of the top resting upon the rear posts, and lugs carried by the side bars to the rear of the 85 posts, said lugs projecting inwardly into the path of movement of the top.

11. A combined table and ironing machine support comprising a supporting frame provided with a supporting ledge adjacent the front thereof, a top pivoted to the frame to swing about a longitudinal axis above said ledge nearer to the front of the frame than the rear thereof and nearer one longitudinal edge of the top than the other, 90 a member pivoted to said top adjacent the edge thereof which is closer to the pivot, said last-mentioned edge of the top being movable past said front ledge within the same and said pivoted member being movable about its pivot to pass said ledge, said pivoted member being adapted to be swung out into a position in which it rests upon said ledge. 95

12. A combined table and ironing machine support comprising a supporting frame having supporting legs at the corners thereof, a reversible table top pivotally mounted on the frame for movement from one horizontal position to a reversed position, about a longitudinal axis intermediate the front and rear of the frame, said supporting legs being located within the confines of the edges of the top when the top is in one of said horizontal positions. 110

13. A combined table and ironing machine support comprising a rectangular supporting frame having supporting legs at the corners thereof, outwardly bowed bars connecting the front and rear legs at opposite 115 120 125 130

ends of the frame, a rectangular table top pivoted to said outwardly bowed end bars for movement about a longitudinal axis from one horizontal position to a reversed position, said top in one of its horizontal positions having both its end and side edges overlying the supporting legs.

14. A combined table and ironing machine support comprising a rectangular supporting frame having supporting legs at the corners thereof, outwardly bowed bars connecting the front and rear legs at opposite ends of the frame, a rectangular table top pivoted to said outwardly bowed end bars for movement about a longitudinal axis from one horizontal position to a reversed position, said top having its end edges projecting beyond said legs, said pivotal axis being nearer the front of the frame than the rear thereof and nearer the front longitudinal edge of the top than the rear whereby the edge of said top nearer the pivotal axis will clear the front supporting legs.

15. A combined table and ironing machine support comprising a rectangular supporting frame having supporting legs at the corners thereof, outwardly bowed bars connecting the front and rear legs at opposite ends of the frame, posts extending upwardly from said end bars between the centers and forward ends thereof, a rectangular reversible table top having a width and length corresponding substantially to the width and length of said frame, a pair of posts fixed to one face of said top adjacent the opposite end thereof and nearer one longitudinal edge than the other, aligned pivots connecting the posts on the end bars and top, ledges on the frame at the rear side thereof above the level of the pivots, lugs projecting inwardly from the end bars rearwardly of said posts, said top being engageable with the top of said ledge and the under side of said lugs at the limits of its movement about its pivotal axis.

16. A combined table and ironing machine support comprising a rectangular supporting frame having a supporting leg at each corner, bars extending from the upper ends of the front legs to the rear legs at opposite ends of the frame, said rear legs having extensions above said end bars, a post extending upwardly from each end bar between the center and forward end thereof, inwardly bowed bars connecting the front and rear legs at opposite ends of the frame below said first-mentioned bars, a longitudinal bar connecting said inwardly bowed bars centrally of the frame, a rectangular top having a pair of posts at its opposite ends and nearer one longitudinal edge thereof than the other, aligned pivots connecting the posts of the top and the posts on the end bars, said top being movable from an upper horizontal position in which it is supported

on said ledge and pivot to a lower reversed position in which it projects forwardly beyond the front of the frame.

17. A combined table and ironing machine support comprising a rectangular supporting frame having a supporting leg at each corner, outwardly bowed bars extending from the upper ends of the front legs to the rear legs at opposite ends of the frame, said rear legs having extensions above said end bars, a post extending upwardly from each end bar between the center and forward end thereof, lugs projecting inwardly from said end bars rearwardly of said posts, inwardly bowed bars connecting the front and rear legs at opposite ends of the frame below said outwardly bowed bars, a longitudinal bar connecting said inwardly bowed bars centrally of the frame, a rectangular top of substantially the same length and width as the frame having a pair of posts at its opposite ends and nearer one longitudinal edge thereof than the other, and aligned pivots connecting the posts of the top and the posts on the end bars, said top being movable from an upper horizontal position in which it is supported on said ledge and pivot to a lower reversed position in which it engages the under side of said lugs and projects forwardly beyond the front of the frame.

18. A combined table and ironing machine support comprising a rectangular supporting frame having a supporting leg at each corner, bars extending from the upper ends of the front legs to the rear legs at opposite ends of the frame, said rear legs having extensions above said end bars, a post extending upwardly from each end bar between the center and forward end thereof, inwardly bowed bars connecting the front and rear legs at opposite ends of the frame below said first-mentioned bars, a longitudinal bar connecting said inwardly bowed bars centrally of the frame, a rectangular top having a pair of posts at its opposite ends and nearer one longitudinal edge thereof than the other, aligned pivots connecting the posts of the top and the posts on the end bars, said top being movable from an upper horizontal position in which it is supported on said ledge and pivot to a lower reversed position in which it projects forwardly beyond the front of the frame, a bracing member connecting the upper ends of the front legs, and a bracing member connecting the upper ends of the rear legs.

19. A combined table and ironing machine support comprising a rigid substantially rectangular frame having supporting legs at the corners thereof, the rear legs being higher than the front legs, end members connecting the front and rear legs, a reversible top pivoted to said end members to swing about a horizontal axis offset with re-

spect to the plane of the top and at a height intermediate that of the front and rear legs, said top in one of its horizontal positions being above its pivotal axis and resting on the rear legs with its forward edge overlying the front supporting legs, said top in its reversed position being below its pivotal axis and overlying the front supporting legs, a panel connecting the upper end portions of the rear supporting legs, and a panel attached to one face of said top and extending along a side edge thereof to bridge the space between the top and front supporting legs when said top is in its upper horizontal position. In testimony whereof, I hereunto affix my signature.

FRANCIS M. CASE.
